UNITED STATES PATENT OFFICE.

WILLIAM HORACE HEFFNER, OF SPARTANBURG, SOUTH CAROLINA.

FOLDING TABLE.

1,220,631.

Specification of Letters Patent. Patented Mar. 27, 1917.

Application filed March 5, 1915. Serial No. 12,325.

To all whom it may concern:

Be it known that I, WILLIAM HORACE HEFFNER, a citizen of the United States, residing at Spartanburg, in the county of 5 Spartanburg and State of South Carolina, have invented new and useful Improvements in Folding Tables, of which the following is a specification.

This invention relates to folding tables, 10 and especially to a folding card table.

The invention has for its object to produce a table which may be conveniently supported on the knees of several players at cards, said table being capable of being folded into small compass when not in use.

A further object of the invention is to produce a simple and convenient foldable table composed of a plurality of hingedly connected sections in combination with a 20 stiffening rod adapted to pass through said sections when extended for the purpose of maintaining them in extended relation while the table is in use.

With these and other ends in view which 25 will readily appear as the nature of the invention is better understood, the same consists in the improved construction and novel arrangement and combination of parts which will be hereinafter fully described and particularly pointed out in the claims.

In the accompanying drawing has been 30 illustrated a simple and preferred form of the invention, it being, however, understood that no limitation is necessarily made to the 35 precise structural details therein exhibited, but that changes, alterations and modifications within the scope of the claims may be resorted to when desired.

In the drawing,— 40 Figure 1 is a perspective view showing the table folded.

Fig. 2 is a top plan view showing the table extended.

Fig. 3 is a sectional view taken on the line 45 3—3 in Fig. 2.

Fig. 4 is a sectional detail view taken on the line 4—4 in Fig. 2.

Fig. 5 is a sectional detail view taken on the line 5—5 in Fig. 2.

50 Corresponding parts in the several figures are denoted by like characters of reference.

The improved table is composed of a plurality of leaves which are hingedly connected together along their edges in such fashion 55 as to fold alternately in opposite directions.

In the illustration four such leaves have

been shown, the same being designated by 15, 16, 17, 18, said leaves being connected together by hinges 19 of well known construction. The leaves are pierced about midway between their ends by transverse bores 20 through which when the table is extended a stiffening rod 21 may be passed, said rod having at one end an eye or handle 22, its other end being threaded, as seen at 23, for 60 engagement with a nut 24 which is inset in the edge of the leaf 18. The leaf 18, it will be seen, lies outermost at one side of the table; the leaf 15 which is outermost at the other side of the table is provided along its 65 outer edge with a groove 25 in which the stiffening rod 21 may be accommodated when the table is folded, keepers 26 being provided for the purpose of retaining the stiffening rod within the groove 25.

The outermost leaves 15 and 18 are provided adjacent to their outer corners with spring clips consisting of flat arched springs 27 secured at one end by fastening means, such as screws 28, the other end being left 70 free. These spring clips will be found extremely convenient for the purpose of retaining in position playing cards that are not in present use. It will be particularly observed that the spring clips 27 are mounted 75 on the faces of the outermost leaves 15 and 18 which are outermost when the leaves are in folded relation and which are uppermost when the leaves are extended for use. It follows that the said spring clips will not 80 interfere with the folding or collapsing of the leaves closely together, thus enabling the table to be folded in the smallest possible 85 compass.

From the foregoing description, taken in 90 connection with the drawing hereto annexed, the operation and advantages of this invention will be readily understood. The improved table may be conveniently supported on the knees or in the laps of several players, the leaves being held securely against collapsing by means of the stiffening rod 21. The table when not in use may be collapsed or folded into small compass, as seen in Fig. 1, and the stiffening rod may then be temporarily retained in the groove 25 by means 95 of keepers 26.

Having thus described the invention, what is claimed as new, is:—

1. A folding table comprising a plurality 110 of hingedly connected leaves provided with transverse bores, the bores of the several

leaves being in longitudinal alinement when the leaves are extended, in combination with a stiffening rod adapted for insertion through said bores, said rod having at one end an eye 5 constituting a handle which when the rod is in engagement with the bores of the leaves lies clear of the edge of one of the outermost leaves.

2. A folding table comprising a plurality 10 of hingedly connected leaves having transverse bores which when the leaves are extended are in longitudinal alinement, one of the outermost leaves having a nut inset in the edge thereof in axial alinement with the bore, in combination with a stiffening rod adapted for insertion through said bores and having one end threaded for engagement with the nut and provided at the other

end with an eye constituting a handle whereby it may be manipulated.

3. A folding table comprising a plurality of hingedly connected leaves and a stiffening rod adapted for coöperative engagement therewith, one of said leaves being provided near one edge thereof with a longitudinal 25 groove and with keepers extending across said groove, said groove and keepers being adapted for retention of the stiffening rod when the table is folded or collapsed.

In testimony whereof I affix my signature 30 in presence of two witnesses.

WILLIAM HORACE HEFFNER.
